UNITED STATES PATENT OFFICE.

HERMAN IHLENBURG, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 20,169, dated September 23, 1890.

Application filed July 26, 1890. Serial No. 360,093. Term of patent 7 years.

To all whom it may concern:

Be it known that I, HERMAN IHLENBURG, a citizen of the United States, and a resident of Philadelphia, Pennsylvania, have invented 5 a new and original Design for a Font of Type, of which the following is a specification.

My design for a font of type is clearly illustrated in the accompanying typographical impression.

10 The leading feature of the design is the ribbon passing through the type characters.

The style of the letters is what may be termed a "fancy block letter," being solid. Passing over and under the letters and entwined around them is a ribbon or band, 15 which when the type are set in form produces an effect of a continuous ribbon. The characters 2, 6, 7, 12, 15, 16, 17, 23, and 25 are terminal characters, while the characters 9, 11, 20 21, 22, 28, 29, and 30 are return or corner characters, and the characters 1, 3, 24, 26, and 27 are line characters. The characters 4, 8, 10,

13, and 14 are used as ornaments to break the continuity of the ribbon.

It will be understood that the letters and 25 numerals of the font may in some instances be set independent of the terminal or return characters.

I claim—

1. In a design for a font of type, the design 30 for the letters and numerals, as described, and as shown in the annexed typographical impression.

2. The design for a font of type, as described, and as shown in the annexed typographical impression. 35

In testimony whereof I have signed my name to this specification in the presence of two subscribing witnesses.

HERMAN IHLENBURG.
